UNITED STATES PATENT OFFICE.

ARTHUR H. MILLER, OF OAKLAND, CALIFORNIA.

GARMENT HANGER.

Application filed August 23, 1926. Serial No. 130,794.

My invention relates to hangers for supporting wearing apparel, and is particularly but not exclusively directed to an improved hanger for trousers.

5 My invention has as its objects: to support clothing in non-wrinkled condition; to support said clothing upright and folded only in its normal creases; to support the upper portion of said garment in stressed condition 10 whereby any wrinkled surfaces are stretched plane either directly by said stress or indirectly by the weight of the garment. Further and ancillary objects of my invention are to provide a garment hanger of utmost 15 simplicity of construction and one which requires no complicated and time-consuming manipulation in use.

Referring to the drawings:

Figure 1 is a side elevation of my improved hanger supporting a pair of trousers by its belt straps. Fig. 2 is an edge elevation of the same. Fig. 3 is an enlarged side elevation of the hanger with the hooks retracted to receive a garment. The dash lines 25 represent the adjusted position of the hooks in the cocked position assumed when the waist of a garment is being held stretched by the hooks. Fig. 4 is a fragmentary view of one of the hooks supporting a garment by 30 its suspender buttons. Fig. 5 is a perspective detail of the hook-ended band in operative position with a portion of hanger broken away to disclose the manner of retaining the pair of hooks in the slot. Fig. 6 35 is a transverse section of a slotted portion of the hanger with the hook-ended band in operative position. The plane of section is indicated by the lines 6—6 in Figs. 1 and 3.

The hanger consists of a body portion 2 curved on its upper edge to receive the 40 shoulder portion of a coat or other garment.

Means are provided for supporting the waist portion 4 of a pair of trousers or other garment. Horizontal slots 6 and 6' are 45 cut, in line with one another, one at each side of the longitudinal center of the body portion 2, in the lower portion of the hanger. A pair of aligned hooks 8, 10, is suspended 50 from each slot by a U-shaped band 12; the bands being conveniently notched at 14 to form the hooks. The legs of the U-shaped bands straddle the portion of the hanger below the slots, and are thereby retained in position. The bands are narrower than 55 the length of slots, to allow movement; but are of substantial width and are appre-

ably thinner than the slots. Thus the bands may be slid to adjusted position along the hanger by a force applied in line with the slots, while any force applied at the hook 60 ends causes the bands to tilt slightly and cock themselves against movement along the slots. (See dash-line position in Fig. 3.) The hooks are purposely made thin, in order to easily receive the suspender buttons 18 of a pair of trousers 20 (see Fig. 4), as well as to simplify and cheapen the manufacture and assembly of the hanger. It is contemplated that the hook-ended bands 12 will be made in a single punching operation 65 from a metal sheet, will be inserted into the slots 6 or 6', and then bent downward at their ends. (See especially Figs. 5 and 6.) The body portion 2, of the hanger, may be made of wood, metal, papier mâché or the 70 like. A wire handle 22 is provided as in the usual coat hanger.

In operation: the bands 12 will be retracted to the position shown in Fig. 3, and the trousers, skirt, or the like, will be hung 80 in folded upright position on the hooks 10, 8, by its belt straps 24, suspender buttons 18, or other available means, and the bands will then be moved outward in the slots to the position, (shown in Fig 1), where the 85 waist band 4 is placed under tension. This tension of the waistband smooths the longitudinal wrinkles out of the trousers, while the weight of the trousers produces a tension which removes transverse wrinkles. 90 This latter tension tends to be greatest along the creases 26, 28, where it is most desired, but is sufficient throughout the intervening area to accomplish its purpose. It is to be especially noted that the trousers are not 95 clamped; the wrinkles are removed and the shape restored by stretching, not by pressing. In fact the hooks 10, 8 of each pair may be spread somewhat if desired to ventilate the garment. By providing a hanger 100 which supports trousers thus in upright position, the annoying and often costly, spilling of articles from the pockets is avoided.

I have described but one embodiment of my invention having several features of advantage. Any or all these advantages might conceivably be secured in modified forms, within the purview of my invention, of the device herein described in detail, and therefore I wish not to be circumscribed beyond 110 the limits of the accompanying claim.

I claim:

A garment hanger comprising a body having spaced collinear horizontal slots formed in its lower portion, and a U-shaped hook-ended band movably supported in each slot with its hook ends depending below said body portion; said hook ends being adapted to support the waist portion of a garment,

and said bands being thinner than the width of said slots whereby a horizontal pull on said hook ends causes the bands to cock ¹⁰ themselves against movement in said slots.

In testimony whereof, I affix my signature.

ARTHUR H. MILLER.
